(57) **CLAIM**

What is claimed is the ornamental design for a product display dispenser, as shown and described.

DESCRIPTION

FIG. 1 is a perspective view of a product display dispenser showing my new design;

FIG. 2 is a top plan view thereof;

FIG. 3 is a bottom plan view thereof;

FIG. 4 is a side elevation view thereof;

FIG. 5 is a front elevation view thereof;

FIG. 6 is a rear elevation view thereof; and,

FIG. 7 is a cross-sectional view of FIG. 4 taken along lines 7—7.

The broken line showing of the environment is for illustrative purposes only and forms no part of the claimed design.
